By Joseph R. Levy

ATTORNEY

UNITED STATES PATENT OFFICE.

LINCOLN KUENEMANN, OF RAMAPO, ASSIGNOR TO WILLIAM I. WALTER,
OF NEW YORK, N. Y.

DESIGN FOR A PATTERN FOR PRINTED FABRICS.

SPECIFICATION forming part of Design No. 24,251, dated April 23, 1895.

Application filed January 9, 1895. Serial No. 534,386. Term of patent 3½ years.

To all whom it may concern:

Be it known that I, LINCOLN KUENEMANN, a subject of the Queen of Great Britain, residing at Ramapo, in the county of Rockland 5 and State of New York, United States of America, have invented and produced a new and original Design for a Pattern for Printed Fabrics, (Case C), of which the following is a specification.

- 10 The leading feature of my design consists of a series of continuous parallel lines, and a line consisting of a series of short intermitted dashes, with short dashes alternately extending from the intermitted dashes.
- 15 In the drawing forming part of this specification, the design for the pattern is shown

consisting of a series of parallel lines, and between two of the said lines is a line of short dashes spaced apart, from the spaces between which extend at right angles to the line of 20 dashes other short dashes, alternately on either side of the said line.

I claim—

The design for a pattern for a printed fabric, substantially as herein shown and de- 25 scribed.

Signed at the city, county, and State of New York this 3d day of January, 1895.

LINCOLN KUENEMANN.
